[57] CLAIM

The ornamental design for a selective call receiver, as shown and described.

DESCRIPTION

FIG. 1 is a front elevational view of a selective call receiver showing our design;

FIG. 2 is a top view thereof;

FIG. 3 is a left side view thereof;

FIG. 4 is a rear elevational view thereof;

FIG. 5 is a bottom view thereof;

FIG. 6 is a right side view thereof;

FIG. 7 is a bottom, front and right side perspective view thereof;

FIG. 8 is a front elevational view of an alternative embodiment of the selective call receiver showing our design;

FIG. 9 is a top view thereof;

FIG. 10 is a left side view thereof;

FIG. 11 is a rear elevational view thereof;

FIG. 12 is a bottom view thereof;

FIG. 13 is a right side view thereof; and,

FIG. 14 is a bottom, front and right side perspective view thereof.
